UNITED STATES PATENT OFFICE

FRANK F. BURTON, OF MOUNT CARMEL, CONNECTICUT, ASSIGNOR TO WINCHESTER REPEATING ARMS COMPANY, OF NEW HAVEN, CONNECTICUT, A CORPORATION OF DELAWARE

ADJUSTABLE LOCKING MECHANISM FOR BREAKDOWN FIREARMS

Application filed March 21, 1930. Serial No. 437,776.

This invention relates to an improvement in adjustable locking-mechanisms for breakdown firearms, such as shotguns and rifles.

The main object of this invention is to provide a breakdown firearm with an adjustable smooth-acting and readily-releasable locking-mechanism which will effectively and securely hold the barrel-unit thereof in operative position with respect to the frame-unit, despite wear and the effects of recoil and counter-recoil of the arm.

With the above and other objects in view as will appear from the following, my invention consists in an adjustable locking-mechanism for breakdown firearms characterized by a manually-retractable spring-pressed locking-bolt mounted in the frame-unit and provided with a locking cam-surface coacting with a complementary cam-surface upon the barrel-unit and an adjustable stop-abutment positioned so as to limit the wedging tendencies between the two said locking cam-surfaces.

My invention further consists in an adjustable locking-mechanism for breakdown firearms characterized as above and having certain other details of construction and combinations of parts as will be hereinafter described and particularly recited in the claims.

In the accompanying drawings:

Fig. 1 is a broken view, partly in side elevation and partly in central longitudinal section, of a double-barreled breakdown shotgun provided with my improved adjustable locking-mechanism;

Fig. 2 is a broken view in transverse horizontal section taken on the line 2—2 of Fig. 1;

Fig. 3 is a broken view in side elevation of the rear end of the barrel-unit;

Fig. 4 is a face view of the rear end of the barrel-unit;

Fig. 5 is a detached view in side elevation of the locking-bolt; and

Fig. 6 is a detached underside view of the locking-bolt.

The embodiment of my invention herein chosen for illustration is, as shown, installed in a double-barreled breakdown shotgun,

though it is obvious that the use of my invention is not so limited, since it may be advantageously employed in connection with other types of breakdown firearms.

The shotgun shown comprises the usual frame-body 10 formed at its bottom edge with a forward extension 11 which in turn is formed with a longitudinal vertically-arranged slot or passage 12 open at its upper end and closed at its bottom end by the forward end of a trigger-plate 13 having a trigger-guard 14 within the looped form of which a pair of triggers 15 are located. The frame 10, as is usual in firearm construction, is secured to the forward end of a butt-stock 16 in any approved manner.

To provide for pivoting the barrel-unit which comprises in the main a pair of barrels 17 and a foreend 18, as well as other incidental features, I provide a transverse trunnion-pin 19 commonly referred to as a "joint pin" and extending across the slot 12 in the extension 11 of the frame-body 10 in the opposite side-walls of which it is supported in the usual manner. This trunnion-pin 70 is partly embedded, so to speak, in the forward wall of the slot 12 but in its central part it has the major portion of its circumference rearwardly exposed within the forward end of the said slot, as clearly shown 75 in Fig. 1 of the drawings.

The barrel-unit is provided in its underside with a longitudinally-arranged centrally-depending lug 20 adapted to fit within the slot 12 of the frame-body 10, as clearly shown in Fig. 1 of the drawings. The forward end of the lug 20 is formed with a forwardly-facing substantially-semicircular transverse notch 21 adapted to rock upon the trunnion-pin 19 before referred to.

The lower forward corner of the extension 11 of the frame 10 is rounded off as at 22 concentrically with the trunnion-pin 19 so that the shoe 23 of the foreend 18 will snugly fit against the frame-body 10 in all positions 85 of the barrel-unit in the swinging movement of the same with respect to the frame-body; the rear face of the said shoe being formed, as shown, with a cylindrically-contoured concave surface 24 conforming to the curva- 95 100

ture of the surface 22 of the extension 11 and resulting in the formation of a relatively-sharp toe 25.

For the purpose of limiting the breakdown movement of the barrel-unit with respect to the frame-body 10, I employ a floating barrel-stop-bar 26 mounted for vertical movement in a transverse slot 27 in the lug 20 before referred to and adapted to have its opposite ends engage with suitable abutments (not shown) in the side walls of the slot 12 in the extension 11.

The rear end-wall of the lug 20 is formed with a notch 28 having an inclined bottom wall forming a locking cam-surface 29, which is adapted to be engaged by the similarly inclined locking cam-surface 30 formed upon the under face of the locking-nose 31 of a reciprocating barrel locking-bolt 32 mounted for movement in a horizontal bore 33, formed in the frame-body 10 and having its forward end intersecting the rear end of the vertical slot 12, before referred to.

The main portion of the locking-bolt 32 is of cylindrical form and is provided at its rear end with a horizontal laterally-offsetting lug 34 formed in its outer end with a coupling-notch 35 for the reception of a cylindrically-contoured operating-finger 36, depending from the under face of a substantially disk-like operating-head 37 having a square axial bore 38 for the reception of the squared lower end of the vertical shank 39 of a finger-lever 40, to which it is secured by a diametrical pin 41.

The finger-lever 40 extends rearward from the shank 39 and is located, as is usual in breakdown firearms, upon the upper face of the frame-body 10 and normally extending over the butt-stock 16.

For the purpose of normally urging the operating-head 37 together with the shank 39 and finger-lever 40 in a clockwise direction, as viewed in Fig. 2, and hence urging the nose 31 of the locking-bolt 32 into the notch 28 of the lug 20, I employ a plunger 42 reciprocating in a rearwardly-opening socket 43 formed in the frame-body 10 (Fig. 2) and having a rearwardly-extending thrust-nose 44 of reduced diameter, engaging a radial thrust-face 45 upon the operating-head 37. The forward end of the plunger 42 is formed with an axial stem 46 which is encircled by a helical spring 47 bearing, at its rear end, against the forward end of the said plunger and, at its forward end, bearing against the bottom wall 48 of the socket 43 before referred to.

From the foregoing, it will be seen that the locking-bolt 32 is constantly urged by the spring 47 into its forwardly-extended position in which its locking cam-surface 30 is engaged with the similar surface 29 upon the barrel-lug 20 with the effect of firmly locking the barrel-unit in its closed position and,

further, that the said bolt may be retracted from its locking position to release the barrel-unit for pivotal movement, in the usual manner about the pin 19, by a swinging movement of the finger-lever 40, in a manner well known in the art of breakdown firearms.

The upper forward end of the locking-nose 31 of the locking-bolt 32 is rearwardly and upwardly sloped to form the cam-surface 49 adapted to be engaged by a complementary cam-surface 50 formed at the lower rear corner of the lug 20 of the barrel-unit for the purpose of automatically-retiring the said bolt, should it per chance be in a projected position when the barrel-unit is swung downward from the position in which it is shown by broken lines in Fig. 1 to the position in which it is shown by full lines in the same figure.

In the operation of the breakdown shotgun herein chosen for the illustration of my invention, the user, when desiring to load the piece, swings the finger-lever 40 and, through the intermediary of the parts 39, 37, 36, 35 and 34, retracts the barrel locking-bolt 32 a distance sufficient to disengage its nose 31 from the notch 28 of the lug 20, thus permitting the barrel-unit to be swung into its breakdown position in which it is shown by broken lines in Fig. 1.

After the loading of the piece, the user swings the barrel-unit into line with the frame-unit in the usual manner and as the said barrel-unit approaches its "home" position, the bolt 32 will be forcibly projected forward by the spring 47 so as to engage the locking cam-surface 30 of its nose 31 with the similar surface 29 of the lug 20, with the effect of locking the barrel-unit in its operative position with respect to the frame-unit.

To check the wedging or jamming action between the locking cam-surfaces 29 and 30 when the locking-bolt is projected forward, as above described, I provide an adjustable stop-abutment in the form of a screw 51, having a flat head 52 and mounted in a threaded-bore 53 preferably located in the lug 20. The rear end of the threaded-bore 53, just referred to, is counterbored as at 54 to provide clearance for the head 52 of the said screw 51, which latter is engaged, as shown in Fig. 1, by the forward end of the locking-bolt 32 to limit the forward movement of the same.

Heretofore, manufacturers have been confronted by a difficult problem in deciding upon the angle of slope of the locking cam-surface of the locking-bolt and the locking cam-surface of the barrel-unit, since if the said surfaces are made but slightly inclined, which is preferable for secure locking of the piece, a marked wedging or jamming action takes place between the said surfaces, due to the forward snapping of the bolt under the urge of its spring and the further for-

ward urge imposed upon the said bolt when the piece recoils. With a bolt so jammed, a very considerable force must be exerted upon the finger-lever 40 in order to overcome this jamming action and retract the bolt. On the other hand, when the coating cam-surfaces are steeply inclined, the counter-recoil of the piece would tend to partially retract the locking-bolt and permit a slight, but none the less objectionable, partial breakdown movement of the barrel-unit.

By means of my invention, I am enabled to employ the locking cam-surfaces 29 and 30 or their equivalent which have a relatively-slight slope and are, therefore, advantageous for the reasons above stated, and effectively prevent any objectionable wedging or jamming action by means of the checking action of the adjustable stop-screw 51.

Should the locking cam-surfaces 29 and 30 wear to a degree sufficient to permit appreciable freedom between the frame-unit and barrel-unit when in their locked positions, such wear may be compensated for without endangering a jamming action by threading the screw 51 forward sufficiently to permit the close engagement of the said cam-surfaces.

It will be understood by those skilled in the art that my invention may assume varied physical forms without departing from my inventive concept and I, therefore, do not limit myself to the specific embodiment herein chosen for illustration, but only as indicated in the appended claims.

I claim:

1. In a breakdown firearm the combination with a relatively-pivoted frame-unit and barrel-unit thereof, of a manually-retirable spring-pressed barrel locking-bolt mounted in the said frame-unit; a locking cam-surface formed upon the said barrel locking-bolt; a complementary locking cam-surface formed upon a portion of the said barrel-unit in position to be engaged by the said cam-surface of the barrel locking-bolt; and an adjustable stop-abutment for the said bolt positioned to limit the movement thereof under the urge of its spring to prevent the wedging of the two said locking cam-surfaces.

2. In a breakdown firearm the combination with a relatively-pivoted frame-unit and barrel-unit thereof, of a reciprocating manually-retirable spring-pressed barrel locking-bolt mounted in the said frame-unit; a locking cam-surface formed upon the said reciprocating barrel locking-bolt; a complementary locking cam-surface formed upon a portion of the said barrel-unit in position to be engaged by the said cam-surface of the barrel locking-bolt; and an adjustable stop-abutment for the said reciprocating bolt positioned to limit the movement thereof under the urge of its spring to prevent the wedging of the two said locking cam-surfaces.

3. In a breakdown firearm the combination with a relatively-pivoted frame-unit and barrel-unit thereof, of a manually-retirable spring-pressed barrel locking-bolt mounted in the said frame-unit; a locking cam-surface formed upon the said barrel locking-bolt; a complementary locking cam-surface formed upon a portion of the said barrel-unit in position to be engaged by the said cam-surface of the barrel locking-bolt; and an adjustable stop-abutment for the said bolt mounted in the said barrel-unit and positioned to limit the movement thereof under the urge of its spring to prevent the wedging of the two said locking cam-surfaces.

4. In a breakdown firearm the combination with a relatively-pivoted frame-unit and barrel-unit thereof, of a barrel-lug depending from the said barrel-unit; a manually-retirable spring-pressed barrel locking-bolt mounted in the said frame-unit; a locking cam-surface formed upon the said barrel locking-bolt; a complementary locking cam-surface formed upon the said barrel-lug in position to be engaged by the said cam-surface of the barrel locking-bolt; and an adjustable stop-abutment positioned to limit the movement of the said bolt under the urge of the spring thereof to prevent the wedging of the two said locking cam-surfaces.

5. In a breakdown firearm the combination with a relatively-pivoted frame-unit and barrel-unit thereof, of a barrel-lug depending from the said barrel-unit; a manually-retirable spring-pressed barrel locking-bolt mounted in the said frame-unit; a locking cam-surface formed upon the said barrel locking-bolt; a complementary locking cam-surface formed upon the said barrel-unit in position to be engaged by the said cam-surface of the barrel locking-bolt; and an adjustable stop-abutment mounted in the said barrel-lug and positioned to limit the movement of the said bolt under the urge of the spring thereof to prevent the wedging of the two said locking cam-surfaces.

6. In a breakdown firearm the combination with a relatively-pivoted frame-unit and barrel-unit thereof, of a barrel-lug depending from the said barrel-unit; a manually-retirable spring-pressed barrel locking-bolt mounted in the said frame-unit; a locking cam-surface formed upon the said barrel locking-bolt; a complementary locking cam-surface formed upon the said barrel-unit in position to be engaged by the said cam-surface of the barrel locking-bolt; and an adjustable stop-screw mounted in the said barrel-lug and positioned to limit the movement of the said bolt under the urge of the spring thereof to prevent the wedging of the two said locking cam-surfaces.

7. In a breakdown firearm the combination with a relatively-pivoted frame-unit

and barrel-unit thereof, of a barrel-lug depending from the said barrel-unit; a manually-retirable spring-pressed barrel locking-bolt mounted in the said frame-unit; a locking cam-surface formed upon the said barrel locking-bolt; a complementary locking cam-surface formed upon the said barrel-unit in position to be engaged by the said cam-surface of the barrel locking-bolt; a threaded-bore formed in the said barrel-lug above the locking cam-surface thereof; and an adjustable stop-screw threaded into the said bore in position to limit the movement of the said bolt under the urge of the spring thereof to prevent the wedging of the two said locking cam-surfaces.

8. In a breakdown firearm the combination with a relatively-pivoted frame-unit and barrel-unit thereof, of a barrel-lug depending from the said barrel-unit; a manually-retirable reciprocating spring-pressed barrel locking-bolt mounted in the said frame-unit; a downwardly-facing locking cam-surface formed upon the said barrel locking-bolt; an upwardly-facing complementary cam-surface formed upon the said barrel-lug in position to be engaged by the said cam-surface of the reciprocating barrel locking-bolt; a substantially-horizontal threaded-bore formed in the said barrel-lug above the locking cam-surface thereof; and an adjustable stop-screw threaded into the said bore in position to limit the movement of the said bolt under the urge of the spring thereof to prevent the wedging of the two said locking cam-surfaces.

In testimony whereof, I have signed this specification.

FRANK F. BURTON.
